UNITED STATES PATENT OFFICE.

BERTHA OBER, OF URBANA, ILLINOIS.

TOY FOR THE PRODUCTION OF LOUD EXPLOSIONS.

SPECIFICATION forming part of Letters Patent No. 285,917, dated October 2, 1883.

Application filed July 17, 1883. (Model.)

To all whom it may concern:

Be it known that I, BERTHA OBER, a citizen of the Empire of Germany, and a resident of Urbana, county of Champaign, and State of Illinois, have invented certain new and useful Improvements in Toys for the Production of Loud Explosions, which I call a "Phonogen;" and I do hereby declare that the following is a full, clear, and exact description thereof, reference being had to the accompanying drawings, and to the letters of reference marked thereon, which form part of this specification.

The object of my invention is to furnish a toy which will take the place of fire-crackers, toy pistols, &c.

It consists of a sheet of paper or other suitable material folded as shown in Figure 1, or substantially so, with a handle attached, as shown in Fig. 2.

20 The sheets of paper or other material may be made of various sizes; but I have found the following to be the size best suited for the purpose desired—viz., twenty-four (24) inches long and fourteen (14) inches wide. Four 25 folds are first made along the lines 1 1 1 1, so that the point *a* will fall upon *a*, *a'* upon *a'*, *a''* upon *a''*, and *a'''* upon *a'''*. Then a fold is made along the line 2 2, so that the two extreme angles will exactly coincide. The whole is then 30 folded along the line 3 3. The last fold is again opened, and the lines 2 and 3 on each side are made to coincide, producing the folds on the lines 4 4 4 4. The sheet will now have the form of a square, in which the fold along 35 the line 3 will be a diagonal and form a triangular body with a single folded edge on the long side and four folded edges on each of the shorter sides. If, now, that portion of the 40 sheet fall upon each other be grasped by the

hand and a rapid motion be made through the air, holding the four edges in the direction of the motion, the air will be forced into the folds, and they will resume the angles along the lines 2 2. This produces a partial vacuum, and is accompanied by a sharp explosive noise, similar to that produced by a fire-cracker. To facilitate the handling of the toy a handle is attached to the part where the two extreme angles of the sheet fall together. The greatest strain on the paper is on the end of the folds 2 2, and also where the handle is attached. To strengthen these places a thin piece of cloth or its equivalent is glued over each part mentioned. Besides this a heavier piece of paper, or other material which will produce the same result, is glued over the part where the handle is attached, in order to give stability to this part.

Having therefore fully described my invention, what I claim is—

1. A toy consisting of a sheet of paper or other suitable material so folded as to produce an explosive sound when suddenly opened by impact against the atmosphere, substantially as described.

2. A toy consisting of a sheet of paper or other suitable material of the size and proportion substantially as described, and folded, first, upon the lines 1 1 1 1; second, upon the line 2 2; third, along the line 3 3; fourth, upon the lines 4 4 4 4, having a handle, 5, attached, as shown, and adapted to be suddenly opened by impact against the atmosphere, thus producing an explosive sound, substantially as and for the purpose described.

BERTHA OBER.
